G. R. HANKS.
DREDGE BUCKET.
APPLICATION FILED AUG. 1, 1921.

1,421,345.

Patented June 27, 1922.

UNITED STATES PATENT OFFICE.

GEORGE R. HANKS, OF HIGH BRIDGE, NEW JERSEY, ASSIGNEE TO TAYLOR-WHARFON IRON AND STEEL COMPANY, OF HIGH BRIDGE, NEW JERSEY, A CORPORATION OF NEW JERSEY.

DREDGE BUCKET.

1,421,345.

Specification of Letters Patent. Patented June 27, 1922.

Application filed August 1, 1921. Serial No. 488,830.

To all whom it may concern:

Be it known that I, GEORGE R. HANKS, a citizen of the United States, residing at High Bridge, in the county of Hunterdon 5 and State of New Jersey, have invented certain new and useful Improvements in Dredge Buckets, of which the following is a specification.

Dredge buckets cast in one piece with the 10 usual central eye and paired eyes for rigging purposes are ponderous constructions and offer serious foundry and treating problems. Especially is this true of buckets made of alloy steel, such as manganese steel, which 15 requires special heat treatment to provide the requisite wearing properties. The difficulties are due largely to the unbalanced area of metal and particularly to the great masses of metal, connecting the eyes with the 20 body, which develop inner checks, cracks and tears. There is no way of detecting these conditions since the casting is apparently sound, so that the ultimate breaking of an eye in service frequently wrecks 25 the entire bucket line and is a heavy item of expense in time, labor, and replacement.

The object of my invention is to provide 30 for sound castings and to provide for uniformity in cooling, following heat treatment, of those regions of the bucket which are subjected to the enormous stresses imposed by ordinary service conditions. I attain 35 this object in the manner and by the means hereinafter described and claimed, reference being had to the accompanying drawings, in which—

Figure 1 is a side elevation of the bottom 40 of a dredge bucket with the eyes and connecting webs formed in accordance with my invention.

Fig. 2 is a vertical sectional view of the same.

Fig. 3 is a section on the line 3—3 of Fig. 2.

Fig. 4 is a section on line 4—4 of Fig. 2.

Fig. 5 is a broken plan of the central eye.

Fig. 6 is a section on line 6—6 of Fig. 2.

As is usual, the bucket bottom 1 is cast 50 with a pair of confronting eyes 2, and with a central eye 3. The eyes 2 are arranged below the bucket bottom, being joined thereto by great masses of metal ultimately developed as web 4. Evidently then they are

of substantial dimension transversely of the bucket. For the purpose of this invention, 55 the metal bounding the eyes is formed with reduced sections by providing recesses 5 separated by bridging elements or webs 6. It will be understood that this construction prevails on both sides of the eye, except that 60 the webs and recesses on one side are staggered with relation to those on the other side. Moreover, the recesses are of gradually increasing size from the relatively upward forward portion of the eye to the relatively lower rear portion thereof, and the recesses increase in number proportionately 65 to the increase in mass or thickness of metal. The webs 4 are also formed on their inner and outer surfaces with recesses 7, which 70 are preferably along the free edge of the web or the region of greatest strain.

The central eye 3 throughout that portion beyond the bucket body is formed with a series of alternating ribs and depressions, 75 respectively indicated at 8 and 9, the terminal rib forming and offset web 10.

The described construction not only simplifies foundry problems, but provides for a greater range or area of heat treatment and 80 for uniform cooling, whereby the development of inner checks and the presence of cracks and tears is largely, if not entirely, obviated.

Having described the nature and object of 85 the invention, I claim:

1. A manganese steel dredge bucket bottom having the metal bounding the eyes thereof formed with re-entrant portions to provide for uniform cooling following heat 90 treatment.

2. A manganese steel dredge bucket bottom having strain serving portions formed with recesses or pockets to ensure uniform 95 cooling under heat treatment.

3. A manganese steel dredge bucket bottom whereof the eyes are formed with alternating webs and recesses.

4. A manganese steel dredge bucket bottom cast with integral eyes formed on both 100 sides with concentric webs and recesses.

5. A manganese steel dredge bucket bottom cast with integral eyes formed with alternating webs and recesses, the recesses increasing in size in proportion to the mass of 105 metal.

6. A manganese steel dredge bucket bottom cast with integral eyes formed on both sides with concentric webs and recesses, the webs and recesses on one side being staggered with respect to the others.

7. A manganese steel dredge bucket bottom cast with a central eye and with paired

eyes and with a cored portion or corridor in the intervening metal, the masses joining the eyes to the body being ribbed and depressed.

In testimony whereof I affix my signature.

GEORGE R. HANKS.
